UNITED STATES PATENT OFFICE

2,577,119

JOINTURE FOR PREFABRICATED
STRUCTURESAlbert J. Fitzgerald, Syracuse, N. Y., assignor to
General Electric Company, a corporation of
New York

Application June 13, 1950, Serial No. 167,817

3 Claims. (Cl. 287—63)

1

My invention relates to a jointure between members of a prefabricated structure. It has more particularly to do with such jointures in decorative structures such as ornamental grills commonly used in radio and television sets.

One of the objects of my invention is to provide such a jointure which is capable of securely holding together several members of such a structure and to prevent vibration between the different members, produced, for example, by loudspeaker operation.

A further object of my invention is to provide such a jointure which may form a decorative component of the ornamental design made up by the grill.

Still another object of my invention is to provide such a jointure which is economical to construct and to assemble in the ornamental grill.

The novel features which I believe to be characteristic of my invention are set forth with particularity in the appended claims.

My invention itself may best be understood by reference to the following description taken in connection with the accompanying drawing in which Fig. 1 represents a decorative grill employing my invention; Fig. 2 is a section on line 2—2 of Fig. 1; Fig. 3 is a rear view of the structure with a part cut away; Fig. 4 is a partially exploded and partially sectionalized view; Fig. 5 is a modification, and Fig. 6 is a section on 6—6 of Fig. 5.

Referring to Fig. 1, I have shown therein at 1 what may be, for example, the front wall of the cabinet of a radio or television set. This wall may have an opening 2 which may be closed, for example, by a suitable tapestry forward of the loudspeaker of the radio set. Forward of this tapestry is the decorative metallic grill illustrated and which may comprise members 3 which are joined together by junctures 4 constructed in accord with my invention. These junctures are desired securely to hold the different members 3 together without danger of vibration or rattling within the juncture 4.

Fig. 2 shows a section of this juncture on the line 2—2 of Fig. 1. It will be observed that it comprises a cylinder 5, one end of which is closed at 6 and into which the members 3 project through slots 7 in the wall of the cylinder. These slots run lengthwise of the wall parallel with the axis of the cylinder and hold the members 3 in a plane parallel with the axis. Preferably the members 3 are cut away as indicated in the drawing so that only projections of the width 8 project through the slots, each of these projections being provided with a notch 9 as indicated.

2

Into these notches are pressed resilient metallic members 10 which bear against the cylinder and against the notch tending to hold the members 3 in place and to draw them toward the axis of the cylinder.

In the bottom of the cylinder adjacent the closed end 6 is a disk 15 of suitable cushion material such as wood, cork, or rubber which may, if desired, have grooves cut therein to receive the edge of the projections 8. These grooves are indicated by dotted lines 16. Preferably, however, the edge of projections 8 embed themselves in the material of the disk 15 under the pressure applied thereto in assembly of the juncture. In the final operation of assembly a closure member 18 which may, if desired, comprise a disk or an annular member having a rim 19 of such dimension as to fit firmly against the sidewall of the cylinder. This member 18 may be firmly pressed 10 as by a punch, or machine press, into the ends of 15 the cylinder 5 until it bears heavily against the resilient members 10 causing them to pull projections 8 inward toward the axis of the cylinder and downward against the cushion material of the disk 15. Friction between the rim 19 and the member 5 securely holds the member 18 in place and the parts in their assembled position with the resilient members 10 under stress.

While I have described the members 10 as 30 resilient any suitable angle member may be used which tends to straighten when put under pressure at the vertex of the angle. If desired a flat rigid metal piece partially broken at the vertex of the angle may be used. Similarly a hinged 35 member may be used. I prefer, however, the resilient members as shown in the drawing.

Fig. 3 shows the rear view of the assembly with the member 18 partially broken away to show the resilient member 10. In this particular form of the invention the members 3 enter the jointure at a small angle to each other so that a single resilient member 10 may be employed to secure two of the members 3 in place.

Fig. 4 is an exploded view of the same assembly 45 showing the closure member 18 removed and better illustrating the form of the resilient member 10.

Fig. 5 differs from the form of the invention 50 illustrated in Figs. 3 and 4 only in that the members 3 enter the jointure at a greater angle thereto thereby making it necessary to employ one resilient member 10 for every member 3, whereas in Fig. 3 one resilient member 10 is used for two resilient members 3.

55 In this case it is preferred that member 10

have the form illustrated at 10' in Fig. 6. It will be seen that the member 10' has a surface 20 bent downward along the inner wall of the cylinder and bifurcated to straddle the projection 8.

It will be observed that 5 conceals the connection between the different members 3, and may be made of the same material and may have the same finish, or a suitably contrasting finish to add to the appearance of the design of the grill work.

While I have shown particular forms of my invention, it will, of course, be understood that various modifications may be made therein and I contemplate by the appended claims to cover all such modifications which may fall within the true spirit and scope of my invention.

What I claim as new and desire to secure by Letters Patent of the United States is:

1. The combination, in a jointure of members in a prefabricated structure, of a cylinder having a closed end, said members projecting through slots in the wall of said cylinder in planes extending radially of said cylinder and parallel with the axis of said cylinder, each member having a notch in the edge thereof opposite said closed end, a member stressed between said notch and the wall of said cylinder, and a closure member for said cylinder bearing against said last member causing it to tend to draw said first members inward and to bear them down against the opposite end of said cylinder thereby to prevent vibration of said members.

2. The combination, in a jointure of members in a prefabricated structure, of a cylinder hav-

ing a closed end, a disk of cushion material in said cylinder adjacent said closed end, said members projecting through slots in the wall of said cylinder in planes extending radially of said cylinder and parallel with the axis of said cylinder, each member having a notch in the edge thereof opposite said closed end, a resilient member stressed between said notch and the wall of said cylinder, and a disk pressed into the opposite end of said cylinder to close it and bear onto said resilient members to cause them to tend to draw said members inward and to bear into said cushion material disk.

3. The combination, in a jointure of members in a prefabricated structure, of a cylinder having a closed end, a disk of cushion material in said cylinder adjacent said closed end having a stem projecting along the axis of said cylinder, said members projecting through slots in said cylinder in planes radial of said cylinder and parallel to its axis, each member having a notch in the edge thereof opposite said closed end, a resilient member stressed between said notch and the wall of said cylinder, and a disk pressed into the opposite end of said cylinder to close it and to bear onto said resilient members to cause them to tend to draw said members inward against said stem and to press them against said cushion material disk thereby to prevent vibration between members of said juncture.

ALBERT J. FITZGERALD.
